CLAIM

The ornamental design for a display screen or portion thereof with graphical user interface as shown and described.

DESCRIPTION

The sole FIGURE is a front view of the claimed design of a display screen or portion thereof with graphical user interface.

The outermost broken lines in the FIGURE illustrate a display screen or portion thereof and form no part of the claimed design. The fluctuating (e.g., wavy) broken line connected to/following the solid line in the charts or graphs in the FIGURE is a part of the claimed design despite being shown as a series of dashes or broken elements. The other broken lines in the FIGURE illustrate portions of the graphical user interface that form no part of the claimed design.
